FRANCIS G. HOTZEL AND JAMES B. ALLEN, OF PUEBLO, COLORADO.

WASHING-MACHINE.

1,136,231.

Specification of Letters Patent. Patented Apr. 20, 1915.

Application filed July 8, 1914. Serial No. 848,740.

To all whom it may concern:

Be it known that we, FRANCIS G. HOTZEL and JAMES B. ALLEN, citizens of the United States, residing at Pueblo, in the county of Pueblo and State of Colorado, have invented a certain new and useful Improvement in Washing Machines, of which the following is a full, clear, and exact description.

Our invention is an improvement in washing machines and its principal object is the provision of a simple, compact machine having the fewest possible number of parts; and one which shall be capable of being opened for charging or removing the clothes without the necessity of lifting or swinging the mechanism carrying top.

Another object of our invention is to so design the machine that wringing means can readily be added and operated by the power means provided for driving the washing machine.

Further and more detailed objects and advantages of our invention will later appear in the specification.

In the single sheet of drawings accompanying this application and forming a part hereof Figure 1 is a side view of the entire machine, a portion of the side of the tub being broken away to disclose the interior portions of the device; Fig. 2 is a perspective, viewed from the right hand side of Fig. 1, of the plunger operating mechanism and the power connections thereto, a portion of the supporting bracket for the plunger rod being broken away; Fig. 3 is a perspective of the guide plate which is immediately on top of the cover; and Fig. 4 is a perspective of the reciprocating sleeve which serves to impart vertical motion to the plunger rod.

Referring to the drawings, in which like numerals of reference indicate like parts in all the figures, 5 is the frame of the machine and 6 the tub which may be of any desired 45 shape and which we have shown as being of a rectangular form.

7 indicates a plunger adapted to be reciprocated up and down in the tub and to thoroughly subject the clothes to the 50 action of the suds and water. The plunger actuating mechanism is mounted on the cover, which cover is mounted to slide on ways in the upper side members 9 of the frame 5.

55 The actuating mechanism comprises a crank shaft 10, journaled in a bracket 11

and having a crank 12 at one end thereof. The crank 12 is connected by a link 13 with the reciprocating skeleton sleeve 14 (see Fig. 4) which encircles the plunger rod 15.

Between the upper and lower rings 16, 17, respectively, of the skeleton sleeve 14 there is received a cam grooved sleeve 18 which is rigidly attached to the plunger rod 15 by rivets 19. The sleeve 18 is formed with a spiral cam groove 20 in which is adapted to travel a roller 21 carried by a bracket 22 on the guide plate 23. This guide plate 23 has a circular opening 40 (see Fig. 3) for the passage of the sleeve 18 and a notch 41 for the vertical member of the skeleton sleeve 14, thus preventing the latter from turning but permitting the sleeve 18 to freely turn. The plunger rod 15, which is hollow and provided with an air escape 75 valve 24 in its top, is further guided near the top by the U bracket 25 through which it passes.

The crank shaft 10 is slotted near its outer end and the drive shaft 26 is also slotted on its adjacent end. A sliding sleeve 27 carries a key on its inner face adapted to enter the slots in the shafts 10 and 26 and forms a means of uniting these shafts; and a set screw 28 may, if desired, be provided in the sleeve 27 to hold it firmly in position. The power shaft 26 is driven by a sprocket chain 29 running over a sprocket wheel 30. The sprocket chain 29 receives its power through suitable speed reducing means from a motor 31, which may be of any suitable kind.

In order that the body of the tub 6 may be of sufficiently small dimensions so that all the clothes therein will be subjected to the action of the plunger and at the same time to permit of easy access to the interior of the tub, we have provided an extension or bay 33 formed as a part of the tub, which bay is adapted to receive substantially half the plunger when the cover is pulled back 100 to open the tub.

While we have shown the frame as considerably larger than the tub and have shown the power means as mounted on this extended part of the frame, this was done 105 for the purpose of preventing confusion in the drawings; and it will be evident that the frame need not be larger than the dimensions of the tub and that a frame of that size will carry the power means as well as 110 one of the relative proportions illustrated.

A section 34 of the cover opposite the bay

side of the tub is hinged to the remainder of the cover as shown in Fig. 1; this swinging section affords a convenient means of inspecting the clothes without the necessity of opening the entire cover and also permits of the substantially full opening of the tub when the cover has been retracted as far as the bay 33 will permit. We also prefer to provide the power shaft 26 with a small pulley 35 for a purpose later to be described.

Operation: Assuming that the cover is drawn back, the tub is charged with the clothes to be washed and the cover is pulled into the position shown in Fig. 1. One or other of the shafts 10, 26, is then turned by hand until the slots are opposite and the sleeve 27 is slipped to the position of Fig. 2 and set in position by the screw 28. The motor 31 then being started motion is communicated to the crank shaft 12 and, through the medium of the link 13, vertical reciprocatory motion is transmitted to the skeleton sleeve 14. Inasmuch as the skeleton sleeve straddles the sleeve 18 on the plunger rod, the latter will be moved up and down and, by means of the roller 21 running in the spiral groove 20, the plunger rod 15 will at the same time be turned in the direction of a right screw when going down and in the opposite direction when coming up. The clothes will thus be subjected not only to an up and down motion but also will be swirled back and forth through the water and suds, thus materially aiding in the cleansing operation. When the washing is done the sleeve 27 may be slipped back to allow the shafts to "break" and the cover 8 may be pulled back to almost clear the full dimensions of the tub.

If it is desired a wringer may be mounted in any convenient place on the machine frame and may be driven by a belt or sprocket chain running on the wheel 35; thus the same motor may be utilized to run both the washing machine and the wringer, which is a great convenience.

Having thus described our invention, what we claim and desire to secure by Letters Patent is:

1. In a washing machine, a tub, a horizontally sliding cover therefor, and a plunger carried by said cover, said tub being provided on the side toward which said cover slides to open said tub with a bay for receiving a portion of said plunger. 55

2. In a washing machine, a tub, a horizontally sliding cover therefor, and a plunger carried by said cover, said tub being provided on the side toward which said cover slides to open said tub with a bay for receiving a portion of said plunger and said cover having a swinging section on its side remote from said bay. 60

3. In a washing machine, a frame, a power shaft mounted on said frame, a pulley on said power shaft, a tub carried by the frame, horizontal cover receiving way on said frame, a cover for said tub mounted to reciprocate on said ways, a plunger carried by said cover and mounted to reciprocate therethrough, plunger reciprocating mechanism comprising a crank shaft also mounted on said cover, and a sliding sleeve for detachably joining said power shaft to said 75 crank shaft.

4. In a washing machine, a tub, a cover therefor, a guide plate mounted on said cover, said guide plate having a plunger rod opening circular in general form but notched at one side, a plunger rod passing through said opening, a crank shaft on said cover, a link connected to said crank shaft, a skeleton sleeve connected to said link and rotatably mounted on said plunger rod with 85 its vertical member engaging said notch in said guide plate, a spirally grooved sleeve secured to said plunger rod and guided in said guide plate, and stationary means mounted on said cover and entering said 90 groove.

In testimony whereof, we have hereunto affixed our signatures in the presence of two witnesses.

FRANCIS G. HOTZEL.
JAMES B. ALLEN.
